[57] CLAIM

The ornamental design for the fishing rig holder, as shown and described.

DESCRIPTION

FIG. 1 is a perspective view of our new fishing rig holder design;

FIG. 2 is a top plan view thereof;

FIG. 3 is a side elevation view thereof with the opposite side a mirror image thereof;

FIG. 4 is an end view as seen from the upper portion of FIG. 2;

FIG. 5 is an opposite end view from FIG. 4 with the item turned over;

FIG. 6 is a bottom plan view thereof; and,

FIG. 7 is a perspective view showing a fishing rig wrapped around one of the pair of extensions and the central retainer strip having the ends drawn back.

The broken lines in FIG. 7 are for illustrative purpose only and forms no part of the claim.
